UNITED STATES PATENT OFFICE.

HAROLD N. HANSEN, OF HIGHWOOD, ILLINOIS, ASSIGNOR OF AN UNDIVIDED INTER-
EST TO HENRY GIESSEL COMPANY, OF CHICAGO, ILLINOIS, A CORPORATION OF
ILLINOIS.

VENTILATOR.

Application filed July 10, 1925. Serial No. 42,726.

This invention relates to improvements in ventilators and has for its object to provide a ventilator efficient in operation and particularly adapted for use with refrigerator 5 or other cars and capable of being arranged for proper functioning in either direction of travel when applied to a car. Another object is to provide a ventilator of this character in which the entrance of back drafts, 10 cinders, water or the like will be prevented. Still another object consists in the provision of a ventilator of this character which may be readily attached to cars of different construction.

15 These and other objects will be more fully set forth and described in the following specification and shown in the accompanying drawings in which

Fig. 1 is a plan view of car with a pair 20 of my ventilators attached;

Fig. 2 is an end elevation of one of my ventilators showing its attachment to one type of car roof;

Fig. 3 is a vertical section along the line 25 3—3 of Fig. 1;

Fig. 4 is a plan view of my ventilator.

Fig. 5 is a plan view with the cap removed;

Fig. 6 is a horizontal section through my 30 ventilator;

Fig. 7 is a view similar to Fig. 2 showing attachment of my ventilator to another type of car roof.

Like numerals refer to like elements 35 throughout the drawings in which A designates generally a refrigerator car with a pair of my ventilators generally indicated by numeral 10 attached thereto at the roof thereof. The ventilator is in the nature of 40 a head having a depending neck 10^a, centrally apertured and threaded for engagement by a threaded pipe 11. Surrounding the neck 10^a is the collar 10^b inclined to accord with the inclination or slant of a car roof 45 or the like. Located above the neck 10^a and in connection therewith is the lower chamber 10^c from which leads the passage 10^d in the chambered partition 10^e, which also communicates with the upper chamber 50 10^f formed by the ceiling or top wall 10^g and the cap 10^h, which is removably secured by screws 12 13 or the like to the top wall 10^g (see Figs. 3 and 4 for example). Extending through the ventilator head are the 55 eduction passages 10ⁱ separated by the chan-

bered partition 10^e (see Fig. 6 for example) each of these passages being provided with the entrance 10^k and the exit 10^l, the former lying in the plane at right angles to the axis of travel or movement of the ventilator, and 60 the latter being located in the plane parallel to the axis of movement or travel. The vertical partition or baffle 10^m is located in each entrance 10^k increasing the eduction effect of the air passing therethrough. In the top 65 wall or ceiling 10^g are provided the elongated ports 10ⁿ (see Fig. 5 for example) affording communication between the chamber 10^f and the eduction passages 10ⁱ, and formed by cross strips or in any suitable 70 manner.

In attachment to the car roof shown in Figs. 1 to 3 for example, the roof face is suitably apertured to permit the insertion of the neck 10^a of the ventilator head, a packing 75 ring or gasket 14 being located beneath the collar 10^b as shown in Fig. 3. The carline A₂ is also apertured to accommodate the neck 10^a and the pipe section 11 and the threaded collar 15 and lock nut 16 being threaded on the pipe 11 to clamp the ventilator in position. In Fig. 7 I have shown the method of attachment of the ventilator to another type of car roof in which dead air or ceiling space A₃ is provided above the false roof A₄. The mounting is substantially similar to that shown in Fig. 3, for example, save that the pipe 11' is of sufficient length to meet the requirement of the dead air space.

The ventilator is preferably mounted with 90 its axis of movement parallel to that of the major axis of the car so that one entrance 10^k faces the front end of the car and the other faces the rear end of the car, the exits 10^l being parallel to the sides of the car. In 95 this arrangement when the car is traveling in either direction an eduction current of air will flow through one of the passages 10ⁱ creating an eduction effect therein and drawing the air from the interior of the car or other chamber to be ventilated through pipe 11, chamber 10^c, chamber baffle 10^d, upper chamber 10^f, and ports 10ⁿ. At the same time some suction will obtain in the other 100 eduction passage 10ⁱ due to flow of the air past or through it, assisting the exhaust of air through the ventilator. The location of the ducts and ports is such as to prevent entrance of back drafts carrying cinders, 105 moisture, dust or the like into the interior 110

of the chamber to be ventilated, regardless of the direction of the surrounding air currents.

It will also be apparent that my ventilator 5 is readily adapted for attachment to any type of car. The cap 10^h being readily removable permits access to the ducts and passages should cleaning or inspection be desirable.

10 It will be obvious that my ventilator is susceptible of modification and I do not wish to be restricted to the form shown and described except as defined in the appended claims.

15 What I claim is:

1. A ventilator comprising a body having a longitudinal passage therethrough, said passage being provided with an entrance and an exit, the exit being arranged at a 20 plane angularly disposed with respect to the plane of the entrance, the said body being further provided with a duct at right angles to the axis of said passage and a chamber located above said passage and in communication therewith, said duct also communicating with said chamber.

2. A ventilator comprising a body portion having a pair of longitudinally arranged passages, the entrances thereto being opposed, each of said passages being further provided with an exit, the planes of such 25

35 exits being angularly disposed with the planes of the entrances, said body being further provided with a duct and a chamber, said duct being located between said passages and communicating with said chamber, said chamber being in communication with said passages.

3. A ventilator comprising a body and a pair of longitudinally arranged passages 40 therethrough, a partition separating said passages, said partition being hollow to form a duct and means to provide communication between said duct and said passages, each of said passages being provided with an entrance and an exit, the exit being in a plane substantially at right angles to the plane of the entrance.

4. A ventilator comprising a body and a pair of longitudinally arranged passages 50 therethrough, a partition separating said passages, said partition being hollow to form a duct and means to provide communication between said duct and said passages, each of said passages being provided with an entrance and an exit, the exit being in a plane substantially at right angles to the plane of the entrance, one entrance being offset with respect to the other.

55 In witness whereof, I hereunto subscribe my name to this specification.

HAROLD N. HANSEN.
